UNITED STATES PATENT OFFICE.

MICHAEL T. DUMSHA, OF PHILADELPHIA, PENNSYLVANIA.

DESIGN FOR AN ORNAMENTAL STAND FOR WATCHES, PICTURES, AND SIMILAR ARTICLES.

Application filed September 20, 1921. Serial No. 502,081. Term of patent 7 years.

To all whom it may concern:

Be it known that I, MICHAEL T. DUMSHA, a citizen of the United States, residing at Philadelphia, in the county of Philadelphia and State of Pennsylvania, have invented a new, original, and ornamental Design for Ornamental Stand for Watches, Pictures and Similar Articles, of which the following is a specification, reference being had to the accompanying drawing, forming a part thereof.

The figure is a face view of an ornamental stand for watches, pictures, and similar articles, showing my new design.

I claim:

The design for an ornamental stand for watches, pictures, and similar articles, as shown.

MICHAEL T. DUMSHA.
